(57) **CLAIM**

The ornamental design for a towel dispenser, as shown and described.

DESCRIPTION

This application relates to the following design applications being filed concurrently herewith:

U.S. Application Ser. No. 29/350,305 entitled Tissue Dispenser

U.S. Application Ser. No. 29/350309 entitled Tissue Dispenser

U.S. Application Ser. No. 29/350314 entitled Soap Dispenser

U.S. Application Ser. No. 29/350312 entitled Air Freshener Dispenser

The disclosures of the foregoing applications are hereby incorporated into this application in their entirety by reference thereto.

FIG. 1 is a top, front, and right side perspective view of a towel dispenser showing my new design;

FIG. 2 is a right side elevation view thereof;

FIG. 3 is a left side elevation view thereof;

FIG. 4 is a front elevation view thereof;

FIG. 5 is a top plan view thereof;

FIG. 6 is a bottom plan view thereof; and,

FIG. 7 is a rear elevation view thereof.

The broken line disclosure is understood to represent portions of the article in which the claimed design is embodied, but which form no part of the claimed design.
